UNITED STATES PATENT OFFICE.

JOHN R. BLAKESLEE, OF CUYAHOGA FALLS, OHIO.

BOLT-HEADING MACHINE.

SPECIFICATION forming part of Letters Patent No. 364,208, dated June 7, 1887.

Application filed September 9, 1886. Serial No. 213,085. (No model.)

To all whom it may concern:

Be it known that I, JOHN R. BLAKESLEE, a citizen of the United States, residing at Cuyahoga Falls, county of Summit, and State of Ohio, have invented certain new and useful Improvements in Bolt-Heading and Upsetting Machines; and I do hereby declare the following to be a description of the same, and of the manner of constructing and using the invention, in such full, clear, concise, and exact terms as to enable any person skilled in the art to which it appertains to construct and use the same, reference being had to the accompanying drawings, forming a part of this specification, the principle of the invention being herein explained and the best mode in which I have contemplated applying that principle, so as to distinguish it from other inventions.

This invention relates to a machine adapted to head bolts, make rivets, upset metal for various purposes, and perform like analogous work.

The controlling object of the invention is to provide a machine which will have a long life and will run smooth in operation. To this end I dispense with cam movement and use crank movement, said crank movement, by reason of the increased wearing-surface, being adapted to last longer in use than a cam movement.

In carrying out my invention I provide a spring device adapted to exert tension upon the movable die-block, said spring device operating in connection with the actuating parts of said movable die-block, so that after the latter has been moved forward in closed position and has gripped the metal said movable die-block may be maintained under spring tension in said closed position a sufficient length of time to allow the header to operate on the metal and to withdraw therefrom. Such a construction and operation of parts permit the use of a crank movement, for without such construction and operation it is apparent that the movable die-block would, by the crank movement, be withdrawn from closed position, and would release the metal from its grip before the header could perform its function.

Referring to the drawings, which represent one form of mechanism for carrying out the

principle of my invention, Figure 1 is a plan view. Fig. 2 is a detail vertical sectional view on line *x* *x* of the first figure. Fig. 3 is a detail plan view, with certain parts broken away, of the spring device which operates in conjunction with the movable die-block. 55

For greater clearness in the drawings, I have omitted from Fig. 1 the two dies and the clamps which hold the latter to their die-blocks. It 60 will therefore be understood that in the complete machine the stationary and the movable die-blocks will be respectively provided with suitable dies.

The driving crank-shaft *A* has its cranks connected, respectively, by links *B* *B'* with the slides *C* and *C'*. Slide *C'* carries the transverse detachable plate *D*, which I call the "breaker." Said breaker has its two vertical side portions engaging with the two bearing-posts *a*, rigid with said slide *C'*, said posts being located on the rearward face of the breaker, while the front face of said breaker has engagement with the vertical curve bearing *b*, rigid on the rear end of link *E*. Said link *E* 75 at its rearward portion is further provided with shoulder *c*, which engages with a cross-bar, *d*, bolted to the forward portion of said slide *C'*. Said shoulder *c* is horizontally convex and fits a corresponding concave bearing 80 formed on said bar *d*. The construction of these parts is such that said link *E* may have lateral radial movement on said curved bearing of bar *d*, and also that said breaker *D* may transmit the forward-moving power to link *E*, 85 while bar *d* transmits rearward-moving power to said link *E*. Said breaker *D* is made of strength sufficient to answer the purpose of thus transmitting forward-moving power to said link *E* in the normal operation of the machine; but should any accident or mismanagement interfere with the normal forward movement of said link *E*, so as to endanger the safety of connecting parts, then said breaker *D* will snap in two under the increased resistance thus put against it as the slide *C'* is on its forward movement, and other parts of the machine will be preserved uninjured. A duplicate breaker *D* may at once be substituted for the broken one, and thus the machine be 90 immediately put again in working condition, said breaker *D* being thus made readily de- 95

tachable from and attachable to its connecting parts of the machine as described for this purpose.

The forward extremity of link E is pivoted 5 by pivot e to the connecting extremities of the two links F F'. Link F is pivoted at its opposite extremity to movable die-block G. Link F' is pivoted at its opposite extremity to stop-block H, which latter is pivoted at its 10 forward extremity by pivot f to the stationary body of the machine. The movement of said block is limited in one direction by stop g thereon coming in contact with bearing h, formed on the stationary part of the machine, 15 and in its opposite movement by shoulder l, formed on its forward portion, coming in contact with bearing m, formed rigid with the stationary body of the machine. The side of 20 of link F is provided with a bearing, n, against which one extremity of a coil-spring, L, engages, said spring and spring-bearing working in a suitable opening, b, formed in the stationary portion of the machine. A set- 25 screw, M, is threaded in said stationary portion of the machine and bears against the extremity of said coil-spring opposite to the extremity which engages with the stop-block.

The operation of the machine is substantially as follows: The movable die-block, with 30 its die, being opened, the metal to be worked on is introduced through opening r, between said movable die and the die secured to stationary die-block N, the proper introduction of said metal being determined by gage s. The forward stroke of slide C' thereupon operates through the described connecting mechanism to bring the movable die up into closed position with the stationary die, thereby gripping 35 the working metal. The header P is then carried forward by slide C, operates on the working metal, and commences its return movement. As soon as the header is clear of 40 the working metal the movable die releases the latter, and the foregoing operation may 45 then be repeated. The general outline of the operation being thus shown, I will now describe the office and function of my spring attachment in the accomplishment of said operation.

It will be understood that in Fig. 1 parts 50 are shown with the movable die-blocks in closed position, and with the link E at the extreme forward terminus of its travel. In Fig. 55 3 the detail parts of this spring attachment are shown in full lines, with the two links F F' having their three pivotal centers in line with each other. Fig. 3 shows in dotted lines the two links F F' in the position they assume 60 when link E is respectively at the extreme forward and rearward termini of its stroke. When the link E commences its forward movement, the stop-block H is in position, with its shoulder l in contact with bearing m, the movable die-block being also in withdrawn position, and the two links F F' forming an ob-

tuse angle on the rearward side of the line which connects the three pivotal centers of said links F F' when in line with each other.

As the link E makes its forward movement the two links F F' are brought into straight line with each other, as shown by the full lines in Fig. 3, the movable die being at this stage of the operation in close face contact with the stationary die. The working metal is now gripped and ready for the header; but the slide E has not up to this time completed its forward movement. It has, however, so far operated upon the toggle joint that the stop-block H has been swung on its pivot 70 f against the spring L, and compressed the latter, the forward head, g, of the stop-block coming into contact with bearing h, as shown in Fig. 3. The link E, in the completion of its forward stroke, then carries the pivot e to 75 the position shown in Fig. 1, thus placing the two links F F' at an angle to each other, as shown in Fig. 1. Spring L thereupon throws the block H into its former position, with shoulder l against bearing m. The link E then commences its return-stroke, and during this initial return movement it brings the two links F F' again into line with each other, and throws the stop-block H with its head g against bearing 80 h, all as shown in Fig. 3. While the link E 85 has thus been completing the extreme portion of its forward stroke and accomplishing the initial portion of its return-stroke the movable die has been maintained in close contact with the stationary die by the tension of spring 90 L against the swinging stop-block and the intermediate connecting parts, said dies thus gripping the working metal a sufficient length of time to allow the header to make its forward stroke act upon the working metal and clear 95 itself from the latter in return movement. As the link E now continues its return movement, the movable die is withdrawn and the working metal is released from its grip. It is apparent that this maintenance of movable die in 100 closed position during a length of time sufficient to allow the header to advance, operate, and withdraw is due to the spring attachment operating in conjunction with the radially-movable link E and the toggle-joint, said combination of parts making it possible for the movable die to be operated by an initial crank movement, in contradistinction to an initial cam movement, of the rotary driving-shaft.

Other forms of embodying and using the 110 principle of my invention may be employed in substitution for the specific form herein shown. It will therefore be understood that omissions, substitutions, and changes may be made as regards the forms and parts herein set forth, 115 provided the principles of construction embraced in the following claims are retained and employed.

I therefore particularly point out and distinctly claim as my invention—

1. In a bolt-heading and upsetting machine, the combination of a driving-shaft carrying two

- cranks, movable gripping die-block G, header P, toggle-links F F', adjustable block H, pitman-connection between one driving-shaft crank and said header, and pitman-connection 5 between the other driving-shaft crank and said toggle-links, substantially as set forth.
2. In a bolt-heading and upsetting machine, the combination of a crank driving-shaft, a movable gripping die-block, adjustable device 10 H, toggle mechanism between the latter and said gripping die-block, and pitman-connection between said toggle mechanism and crank-shaft, substantially as set forth.
3. In a bolt-heading and upsetting machine, 15 the combination of a crank driving-shaft, a movable gripping die-block, toggle-links F F', spring adjustable device H, and intermediate connection between said toggle-links and said crank-shaft, substantially as set forth.
- 20 4. In a bolt-heading and upsetting machine, the combination of a crank driving-shaft, A, toggle-links F F', intermediate connection between said parts, movable gripping die-block G, and spring-pressed adjustable block H, substantially as set forth.
- 25 5. In a bolt-heading and upsetting machine, the combination, with a driving-shaft provided with a crank, a movable die-block, and intermediate mechanism, of toggle-jointed arms 30 and a spring-pressed pivotal block, substantially as set forth.
- 35 6. In a bolt-heading and upsetting machine, the combination, with a driving-shaft provided with a crank, a movable die-block, and intermediate mechanism, of a pivotal spring-pressed block, and toggle-jointed arms connecting said die-block and said pivotal block, said intermediate crank connecting mechanism being connected to said toggle-joint, substantially as 40 set forth.
- 45 7. In a bolt-heading and upsetting machine, the combination, with a movable die-block and a spring-pressed pivotal block, of a toggle-joint connecting the two, and a link connecting said toggle-joint with a rectilinear reciprocating slide, said link loosely connected with the slide and adapted to have radial swinging movement, substantially as set forth.
8. In a bolt-heading and upsetting machine, the combination, with a movable die-block, a 50 spring-pressed block, and a toggle-joint connecting the two, of a link connecting said toggle-joint with a reciprocating slide, said spring-pressed block operating to maintain the movable die-block in stationary closed position while said link is making the last portion of its forward stroke and the first portion of its return-stroke, substantially as set forth. 55
9. In a bolt-heading and upsetting machine, the combination, with a movable die, a spring-pressed block, and a toggle-joint connecting the two, of a link connecting said toggle-joint with a reciprocating slide, said spring-pressed block operating to maintain the movable die in stationary closed position while said link is 60 making the last portion of its forward stroke and the first portion of its return-stroke, said spring-pressed block provided with stops which limit its pivotal movement, substantially as set forth. 65
10. In a bolt-heading and upsetting machine, the combination, with a movable die-block, G, and a spring-pressed pivotal block, H, of two links, F F', respectively pivoted to said two blocks at their opposite extremities, 70 while the connecting extremities are pivoted to link E, said link E connecting with slide C', substantially as set forth. 75
11. In a bolt-heading and upsetting machine, the combination, with a movable block, 80 G, links F F' E, and pivotal block H, of spring L and spring-adjusting device M, substantially as set forth.
12. In a bolt-heading and upsetting machine, the combination, with a spring-pressed 85 pivotal block, H, provided with stops g l, of bearings h m, formed on the stationary portions of the machine, substantially as set forth.

In testimony that I claim the foregoing to be my invention I have hereunto set my hand 90 this 14th day of June, A. D. 1886.

JOHN R. BLAKESLEE.
